UNITED STATES PATENT OFFICE.

ROBERT K. WINNING, OF WAUWATOSA, WISCONSIN, ASSIGNOR TO CLUM MANUFACTURING COMPANY, OF MILWAUKEE, WISCONSIN, A CORPORATION OF WISCONSIN.

LIGHT-DIMMING SWITCH.

Application filed May 19, 1927. Serial No. 192,519.

This invention relates to improvements in light dimming switches.

It is the primary object of the invention to provide a foot operated switch adapted to connect either of two live terminals alternatively and successively with a current supply terminal during successive operations of the switch, the switch being so designed that it is not possible to operate the switch in such a manner as to leave both circuits open.

While the switch made in accordance with this invention has other fields of utility, it is particularly serviceable in the above indicated field for the reason that the operator cannot properly control a foot switch so designed as to require any delicate adjustment. It is highly objectionable to have a foot switch so constructed that anything less than a full operating movement of the control member will leave both circuits open. It is one of the important purposes of the present invention to provide a novel construction insuring that if the switch operates at all, it will make its full movement to its new position. Thus the operator will never be left without one light or the other, when the switch is used to control the bright and dim headlights of a motor vehicle.

Further objects of the invention relate to compactness of organization, the elimination of parts, economy of manufacture and simplicity of design. It will be understood that from these standpoints the invention is not confined to the particular function of controlling the change from bright to dim of automobile headlight circuits or even to the more general field of automotive lighting control.

In the drawings:

Figure 1 is a side elevation of my improved switch.

Figure 2 is a front elevation.

Figure 3 is a detail view taken in section in the plane indicated by line 3-3 in Figure 1.

Figure 4 is a side elevation of the casing for the switch mechanism shown in Figures 1, 2, and 3.

Figure 5 is a detail of the actuating rack.

Figure 6 is a detail of the mounting of the moving switch contactor on its driving sleeve.

Like parts are identified by the same reference characters throughout the several views.

The frame 10 upon which the switch mechanism is assembled comprises merely a strip of sheet metal bent along transverse lines at 11 and 12 to provide a top wall 13, a front wall 14 and a rear wall 15. Integral 60 ears 16 and 17 project horizontally from the ends of the top wall 13 and are apertured to receive mounting bolts or screws.

A terminal head 19 is shouldered at 20 to seat in a correspondingly formed opening in 65 the front wall 14 of the switch frame. The two flat sides of the terminal head and the correspondingly formed margins of the opening permit no possible tendency of the terminal head to rotate in its mounting. An 70 axis pin or shaft 21 is riveted at its ends to engage the rear wall 15 of the switch to the terminal head and thus serves to hold the terminal head in the position defined.

The moving switch contactor comprises a 75 thin disc of sheet metal 25 mounted on a carrier disc 26 to which it is engaged by means of tongues 27. Contacts 28 are embossed to project forwardly from the face of disc 25 to a position where engaged with 80 the fixed terminal contacts 29, 30, 31 and 32. Terminal contacts 29 and 30 are connected by the strip conductor 33 so that the contacts 28 of the moving contacting device will engage them successively and will simultaneously make connection with a fixed terminal 85 diametrically opposite. During successive switch operations, terminal 29 will be connected electrically to terminal 31 and then terminal 30 will be connected to terminal 32, 90 these connections being established alternately in each repetition of the cycle of operations.

The means for operating the moving contactor and maintaining it in operative relation to the terminal head will now be described.

For this particular invention the control member consists of a reciprocable plunger or foot button which includes a rod 35 and cap 100 36. The rod is guided for vertical reciprocation by the guide sleeve 37 mounted in the top plate 13 of the frame. The compression spring 38 encircles guide sleeve 37 and is seated within the cap 36 to maintain the rod 105 35 in an elevated position, the rod being riveted at 39 to the cap 36.

Rod 35 carries a rack 40 stamped from sheet metal and provided integrally with spaced heads 41 and 42. Head 41 is aper-

tured to fit upon rod 35 while head 42 fits upon the reduced end of the rod which is riveted thereover at 43. The material of this stamping is cut away to leave narrow strips of metal at 44 which serve as rack teeth which, in the limited reciprocative movement of the plunger, interact with the teeth 45 of the ratchet member 46.

The driving ratchet member 46 comprises a disc with three teeth 45 from which the ratchet pawls or tongues 47 are stamped to project integrally. The driving ratchet is mounted for rotation on shaft 21 and is spaced from the rear wall of the switch frame by means of a collar 48.

The ratchet pawls 47 interact with similarly formed pawls 49 which are opposed thereto on the face of the driving ratchet member 50. The driven ratchet member 50 is carried by and imparts motion to squared sleeve 52 which is in splined relation to the contact carrier fibre disc 26. A compression spring 55 interposed between the driven ratchet member 50 and the contact carrier disc 26 permits the dual function of maintaining the ratchet and the switch parts in their proper respective relations. It will be noted that the terminals 32 are tubular and provide recesses at their extremities into which the moving contact protuberances 28 enter in reaching positions of contact. Spring 55 furnishes the pressure necessary to effect proper engagement of the parts in such positions and it yieldably permits the protuberances to leave the terminals upon each operation of the switches.

The impositive definition of the switch positions arises from the above described organization of the switch contacts in which the switch terminal recess is sufficient to hold the switch against movement while the dogs or pawls 47 of the driving ratchet member 46 force their way past the complementary pawls 49 of the driven ratchet member 50. The relative yielding of the two ratchet members in an axial direction to permit the pawls to pass each other in this manner is made possible by the provision of spring 55 and the splined connection between the squared sleeve 52 and the moving switch contactor. When the driving ratchet member is rotated in the reverse direction, however, the square cut ends of its pawls will engage the similarly formed ends of the opposing pawls on the driven ratchet member, thereby establishing a positive driving connection between such members for the rotation of the switch contactor to a new position.

It is particularly to be noted that the switch mechanism is so formed that the ratchet action takes place on the downward movement of the control button or plunger. There is no adjustment of the switch effected until the control plunger is moving up-

wardly under the compression of spring 38. The ratchet pawls or teeth 47 and 49 are so spaced that when the plunger makes a full stroke the motion transmitted through the ratchet to the switch contactor will be 70 exactly sufficient to advance the contactor to a new operative position at the next succeeding station. If the downward movement of the plunger is less than the full stroke required to effect switch adjustment from one 75 station to another the inclined surfaces of the ratchet pawls will still be engaged, consequently there will be no switch movement on the return stroke. It is only when the plunger makes a full stroke that the two 80 pawls pass each other completely so as to bring their squared ends into engagement for the transmission of movement to the switch mechanism on the return stroke of 85 the plunger.

While the device thus far described is complete in itself, it is preferred to encase the operating mechanism in a cover which co-operates with the frame 10 to keep dust and dirt from the moving parts. The casing comprises a narrow strip of metal shown in elevation in Figure 4 stamped to fit about the side margins of the front and rear frame walls 14 and 15. The width of the casing strip 56 is just sufficient to enable it to rest upon such margins, and its intermediate portion is embossed inwardly at 57 to fit between such margins and thereby to fix the position of the casing strip with reference to the frame.

The ends of the casing strip are turned upwardly at 58 and apertured to receive rivets 59, whereby it is permanently attached to the ears 16 and 17 of the switch frame. The rivets employed for this purpose are 105 tubular so that securing bolts or screws may be passed therethrough to mount the device as above described.

It will be noted that the several terminal contacts are equidistant from the axis of shaft 21 and are angularly spaced at 60° in the set and 120° between sets. The rotatable contactor has its contacts at the same rotatable distance from the center of shaft 21 and spaced 120° apart. As a result the conclusion of each rotatable adjustment of the contactor will find two of the contacts 28 engaged with terminals of opposite sets and terminals 31 and 32 will be engaged alternatively so that either one or the other of them will at all times be supplied with current from the interconnected terminals 29 and 30. The same result might be achieved with two moving contact buttons, but a 90° rotation would be required. The organization above described accomplishes the result with a 60° rotation and a correspondingly simplified actuating mechanism.

I claim:

1. A combination with a switch mecha-

nism and a clutch mechanism including co-axial parts axially movable in the respective mechanisms, of a spring pressing oppositely upon said parts and adapted yieldably to maintain each in its proper relative relation to its respective mechanism.

2. In a device of the character described, the combination with a terminal head provided with relatively fixed contacts, of a 10 contactor rotatably mounted in association with said head for operative engagement with said contacts, a one-way clutch including an axially adjustable part in rotative connection with said contactor, and spring 15 means interposed between said movable clutch part and contactor, and by its reaction adapted to press together the spring of said clutch and said switch.

3. In a device of the character described, 20 the combination with a switch mechanism and a clutch mechanism including rotatably connected and axially movable parts in axial alignment in the respective mechanisms, of a co-axial compression spring seated at its 25 ends against said parts and yieldably pressing said parts in opposite directions to their proper respective positions in said mechanisms.

4. In a device of the character described, 30 the combination of a switch mechanism and a clutch mechanism, including co-axially rotatable parts in the respective mechanisms, a shaft for the support of said parts, a splined connection between said parts adapt- 35 ed to permit them to move toward each other upon said shaft elements relatively fixed against axial movement and complementary to said parts in the respective mechanisms, and a compression spring interposed between 40 said parts and adapted in its reaction to press each such part toward its respective complementary element.

5. In a device of the character described, 45 a combination with a switch mechanism and a clutch mechanism each of which includes an element relatively fixed against axial movement, of a shaft extending between said elements, a sleeve upon said shaft, axially movable parts respectively in said clutch 50 mechanism and said switch mechanism and mounted on said sleeve in splined connection with each other and complementary to the axially fixed elements of their respective mechanisms, and a spring wound about said 55 sleeve and seated against said parts whereby yieldably to maintain said parts in operative relation to said elements.

6. A device of the character described, 60 including a terminal head provided with terminal contacts, a rotatable contactor associated with said head, an actuating means including a pinion connected to impart motion to said contactor, a reciprocable head, and a rack connected with said head and 65 meshed with teeth of said pinion, said rack

comprising a stamping having upturned ears engaging said rod and an intermediate upturned flange notched to provide teeth in mesh with said pinion.

7. A device of the character described, 70 including a frame having front and rear face members connected by a top member, a terminal head seated in one of said face members and provided with terminal contacts, a transverse shaft between said face members 75 fixing said terminal head to its seat, and a movable switch contactor between said face members upon said shaft.

8. A device of the character described, 80 including a frame having front and rear face members connected by a top member, a terminal head seated in one of said face members and provided with terminal contacts, a transverse shaft between said face members fixing said terminal head to its seat, 85 and a movable switch contactor between said face members upon said shaft, together with actuating means for said contactor, including a plunger reciprocably mounted in said top member and motion transmitting connections including a rack and pinion between said plunger and said contactor.

9. A device of the character described, 90 including a pair of spaced plates, insulated terminal contacts supported in one of said plates, a moving contactor between said plates in a position to engage said contacts in step by step rotation, a one-way clutch adapted to produce said rotation and including a pair of complementary ratchet members 100 aligned with each other and said contactor, one of said ratchet members being fixed against axial movement and the other being in splined connection with said contactor, means for oscillating said first mentioned ratchet member, and compression spring means interposed between said second ratchet member and said contactor.

10. A switch mechanism including a terminal head provided with terminals arranged in pairs at like radial distances from a common center, the terminals of each pair being spaced at like distances and the space between the pairs being double the distance; of a switch contactor co-axial with said center and provided at a radius for registration upon said terminals with three contact elements in mutually conductive relation and spaced at equal angular distances whereby in each successive movement of said contactor two of said elements are adapted to bridge between terminals of opposite sets.

11. A switch mechanism including a terminal head provided with terminals arranged in pairs at like radial distances from a common center, the terminals of each pair being spaced at like distances and the space between the pairs being double the distance; of a switch contactor co-axial with said center and provided at a radius for registration 125

- upon said terminals with three contact elements in mutually conductive relation and spaced at equal angular distances whereby in each successive movement of said contactor two of said elements are adapted to bridge between terminals of opposite sets, and alternate terminals of one of said sets.
12. In a device of the character described, the combination with a contactor movable between successive stations in a step by step movement and provided with spaced projecting contacts mutually in electrical connection, of two sets of terminal contacts adapted to be engaged by the contacts of said contactor, one set of terminal contacts being mutually connected electrically and the contacts of the other set being mutually insulated and so positioned that one or the

other thereof is alternatively in circuit with the terminal contacts of said first mentioned set at each stationary position of said contactor.

13. A device of the character described, including a terminal head provided with contacts, a rotatable switch element associated with said head and adapted to interact with said contacts, actuating means within said switch element comprising a reciprocable rack, and a pair of clutch disks provided on their opposing faces with pawl mechanism adapted for one way engagement only, one of said disks being connected with said switch element and the other being provided with peripheral teeth meshing with said rack.

ROBERT K. WINNING.
